ALBERT E. SMITH, OF WASHINGTON, DISTRICT OF COLUMBIA, ASSIGNEE TO THE T. L. SMITH COMPANY, OF MILWAUKEE, WISCONSIN, A CORPORATION OF WISCONSIN.

CONCRETE-MIXER AND THE LIKE.

1,129,132.

Specification of Letters Patent. Patented Feb. 23, 1915.

Application filed March 26, 1913. Serial No. 756,903.

To all whom it may concern:

Be it known that I, ALBERT E. SMITH, a citizen of the United States, residing at Washington, in the District of Columbia, 5 have invented a new and useful Loading Device for Concrete-Mixers and the like, of which the following is a specification.

My invention relates to loading devices for the rotatable drums of concrete mixers 10 and similar machines, and the objects of my invention are to increase the simplicity, durability and mechanical efficiency of devices of this character. I attain these objects by the construction shown in the accompanying 15 drawing, in which—

Figure 1 is a view of the machine transverse to the axis of the rotating drum, some parts being shown in section; Fig. 2 is a view of the machine looking along the axis 20 of the rotating drum; Figs. 3, 4 and 5 are fragmentary views of details of construction.

The rotatable drum of the concrete mixer or like machine is designated by numeral 10. 25 This drum is supported and driven in any manner usual in machines of the non-tilting type, and has a feed opening 11 and a discharge opening 12 at its opposite ends.

13 is a loading bucket connected to the 30 loading chute 14, which chute enters the drum 10 through its feed opening. The bucket is shown in its lowered position, resting on the ground, and while in this position, the door 15 may be opened by swinging it upward on the hinges 16, and the material to be loaded in the drum is placed in the bucket 13. The door 15 may be held closed by any convenient means, as the latches 17, to prevent material spilling out 35 as the bucket is elevated.

The chute 14 is supported in a ring 18 supported from the machine frame by arms 19, legs 20 and braces 21 of any convenient form. The bearing ring 22 is formed integral with, or rigidly attached to, the chute 14, and is provided with a projecting rib or flange 23 confined within the ring 18 by the ring plate 24 which is bolted to ring 18. The ring 18, the bearing of ring 22, and the 45 drum entering end of chute 14 are all coaxial with the drum 10 and its feed opening 11. The gear sector 25 is also attached to the chute 14 or ring 18, and is engaged by the pinion 26 on the shaft 27. As the loading bucket 13 is to be operated intermit-

tently at will, a friction clutch is placed somewhere between the pinion 26 and its driving means. In the example shown, the gear 28 runs loose on the shaft 27 and is connected therewith at will by means of the 60 external friction member 29 attached to the gear being engaged by the internal friction member 30 which is slideable on the shaft 27 but is constrained to rotate therewith. A lever 31 actuates the friction member 30 into 65 and out of engagement with the member 29 in the usual manner.

32 is a brake wheel attached to the shaft 27 and is engaged by a brake band 33 by means of the brake lever 34.

In operation, the bucket 13 and its attached chute 14 are actuated by the gearing 26 and 25 to swing around the axis of the drum as a center line until elevated sufficiently to cause the contained material to 75 slide by gravity through the chute 14 into the drum. The friction clutch is then released and the return of the bucket to ground is controlled by the brake 32—33. 70 To prevent the bucket being elevated too far 80 through carelessness, a knock-off is provided consisting of a rod 35 engaging lever 31 and engaged by a cam lug 36 on the gear sector 25. By swinging the loading bucket around the drum's axis the overhang of the load 85 outside of the machine is constant and the minimum possible.

In the example shown in Figs. 1 and 2, the mixer is of the non-tilting type. When the loader is to be used in connection with a 90 mixer of the tilting type, the mouth of the chute 14 must be withdrawn from the drum when the loading bucket is in its lowered position to allow the drum to swing past the chute in tilting, and while the bucket is discharging to the drum, the chute should enter the drum slightly to obviate spilling. This movement of the chute into and out of the drum is accomplished by the means shown in Figs. 3, 4 and 5. Fig. 3 shows a ring 181 100 to be used in place of the bearing ring 18 of Fig. 1. This ring carries cam lugs 231 to be used in place of the rib 23 of Fig. 1. These cam lugs are similar to partial screw threads, and engage in corresponding 105 grooves 222 in the ring 221, which takes the place of the ring 22 attached to the chute 14. Fig. 4 shows a part of the rings 181 and 221 with the cam lug 231 engaged in the groove 222. Fig. 5 is a cross section on the line 110

5—5 of Fig. 4. As the ring 221 is turned in the ring 181 while the bucket 13 is being elevated, 221 with the attached chute 14 will be moved toward the drum and on lowering it will be withdrawn. While this movement is taking place, the gears 25 and 26 will change their relative positions slightly longitudinally of the gear teeth.

It will be understood that the illustration 10 of this device is merely by way of example and changes may be made in details without departing from the invention specified in the claims.

What I claim as my invention is:—

15 1. A loading device for a rotatable mixing drum having an axial feed opening, consisting of a bearing parallel with the axis of the drum, a loading bucket independent of the drum supported by said bearing and means for intermittently swinging said bucket on said bearing around the axis thereof as a center line.

20 2. A loading device for a rotatable mixing drum having an axial feed opening, consisting of a bearing coaxial with the drum, a loading bucket independent of the drum supported by said bearing and means for intermittently swinging said bucket on said bearing around the axis of the drum as a 25 center line.

25 3. A loading device for a rotatable mixing drum having an axial feed opening, consisting of an annular bearing coaxial with the drum, a loading bucket independent of the drum supported in said bearing and means for intermittently swinging said bucket in said bearing around the axis of the drum as a center line.

40 4. A loading device for a rotatable mixing drum having an axial feed opening, consisting of an annular bearing coaxial with the drum, a loading bucket independent of the drum engaging said annular bearing and means for swinging said bucket in said bearing, said bucket having its discharge chute extending through said annular bearing.

45 5. A loading device for a rotatable mixing drum having an axial feed opening, consisting of an annular bearing coaxial with the drum, a loading bucket independent of the drum having an attached chute extending through said annular bearing, guide bearings positioning said chute along the 55 drum's axis and means for elevating said bucket around the drum's axis.

6. A loading device for a rotatable mix-

ing drum having an axial feed opening consisting of a supporting member having internal cylindrical and radial bearings coaxial with the drum, a loading bucket independent of the drum having an attached chute extending through said supporting member and engaging said bearings, and means for elevating said bucket around the 60 axis of the drum.

7. A loading device for a rotatable mixing drum having an axial feed opening, consisting of a supporting member having a cylindrical bearing coaxial with the drum, a loading bucket having an attached chute extending through and engaging said bearing, means for elevating said bucket around the axis of the drum and means for moving the mouth of the chute toward the drum as 75 the bucket is elevated.

8. A loading device for a rotatable mixing drum having an axial feed opening, consisting of a supporting member having a cylindrical bearing coaxial with the drum, a loading bucket having an attached chute extending through and engaging said bearing, means for elevating said bucket around the axis of the drum and cam lugs on one of said bearing members engaging corresponding grooves in the other bearing member, said lugs and grooves being arranged to move said chute toward the drum while the bucket is being elevated and to retract the chute while the bucket is being lowered.

9. A loading device for a rotatable mixing drum having an axial feed opening, consisting of a supporting member having a bearing coaxial with the drum, a loading bucket having a rigidly attached chute supported by said bearing, a gear sector attached to said bucket and chute and mechanism engaging said gear sector adapted to elevate said bucket around the axis of the drum.

10. A loading device for a rotatable mixing drum having an axial feed opening, consisting of a supporting member having a bearing coaxial with the drum, a loading bucket independent of the drum supported by said bearing, a train of gearing including a friction clutch for elevating said bucket, and a brake adapted to control the lowering of said bucket.
